Claims priority, application Germany June 11, 1960

8 Claims. (Cl. 260—397.4)

This invention relates to steroids. More particularly, it is directed to compounds of the following Formula II:

wherein:

R₁ is a member of the group consisting of H, CH₃, F and Cl;

R₂ is a member of the group consisting of H and acyl;

R₃ is a lower aliphatic carboxylic acid radical; and

Z is a member of the group consisting of (H,H), (H,CH₃) and =CH₂.

The subject matter of the present invention, the steroid-3-enol-acylates of the above Formula II can be prepared by converting a 3-keto-4,6-diene steroid of Formula I:

in which:

R₁=H; CH₃; F or Cl;

R₂=H or acyl;

Z=(H,H), (H,CH₃) or =CH₂

by treatment with a lower aliphatic enol-acetyating agent, into the corresponding steroid-3-enol-acylate.

It has now been found that the oral action of steroid-3-enol-acylates of Formula II obtained in accordance with the invention is substantially greater than that of the basic steroids of Formula I. From U.S. Patent 2,889,342, there are known steroid-3-enol-acylates which have been prepared from 3-keto-4-ene-steroids which are saturated in 6, 7-position. As has been proven in the Clauberg test, the triply unsaturated steroid-3-enol-acylates obtained in accordance with the invention have a considerably stronger progestational effect upon oral administration than the doubly unsaturated steroid-3-enol-acylates described in U.S. Patent 2,889,342. Thus for 16-methylene-2,4,6-pregnatriene-20-one-3,17 α -diol-diacetate, there was found 3400 times the effect of progesterone. The corresponding 16-methylene-3,5-pregnadiene - 20 - one-

2

3,17 α -diol-diacetate was on the other hand only 425 times more effective than progesterone.

The enol-acylation is carried out by the customary methods. It is advantageous for instance to use a mixture of a lower aliphatic carbonyl chloride and a lower aliphatic carboxylic anhydride as well as possibly in the presence of an organic base such as pyridine. The enol-acylation can also be carried out with the use of a mixture of the corresponding carboxylic anhydride with an organic base such as pyridine.

- 5 In these enol-acylations, it is not necessary to add a special solvent, since the initial steroids dissolve in the mixtures used as enol-acylating agent. The reaction temperatures are between room temperature and the boiling point of the mixture of the lower 15 aliphatic acid halides and anhydrides used as enol-acylating agent. The reaction times vary between a few hours and two days, depending on the reaction temperatures applied.

The enol-acylation in accordance with the invention 20 can also be carried out with the use of isopropenyl acetate which is customarily used as enol-acetylating agent. In this case, benzene or any other aromatic hydrocarbon such as toluene or xylene is used as solvent. It is furthermore advisable in this reaction to add an acid catalyst, 25 for instance, small amounts of p-toluene sulfonic acid, to the reaction mixture:

The esterifying moiety of R₂ may be the acyl radical of one of the customary esterifying acids used in the steroid art to provide pharmaceutically acceptable esters, as for 30 example, acetic acid and the higher homologues thereof having up to 10 carbon atoms. Thus, the 17 α -esters include the following: the formate, the acetate, the propionate, the butyrate, the isobutyrate, the valerate, the capronate, the enanthate, the caprylate etc.

35 R₃ is a lower aliphatic acyl radical having up to 5 carbon atoms. Thus, the present invention includes the 3-enolacylates of the following acids: acetic acid, propionic acid, butyric acid, valeric acid, methyl butyric acid and trimethyl acetic acid.

40 As starting material, there can be used, for instance, the following compounds:

4,6-pregnadiene-3,20-dione-17 α -ol

16-methylene-4,6-pregnadiene-3,20-dione-17 α -ol

16-methylene-6-methyl-4,6-pregnadiene-3,20-

dione-17 α -ol

16-methylene-6-fluoro-4,6-pregnadiene-3,20-dione-17 α -ol

16-methylene-6-chloro-4,6-pregnadiene-3,20-dione-17 α -ol

50 6-methyl-4,6-pregnadiene-3,20-dione-17 α -ol

6-chloro-4,6-pregnadiene-3,20-dione-17 α -ol

6-fluoro-4,6-pregnadiene-3,20-dione-17 α -ol

55 As starting material, the 17 α -acylates, particularly the 17 α -acetates, of the above compounds also enter into consideration.

A hydroxyl group in 17 α -position in the starting material can be co-esterified in the enol-acylation.

By the foregoing method, there are obtained, for instance, the following steroid-3-enol-acylates:

2,4,6-pregnatriene-20-one-3,17 α -diol-diacetate

16-methylene-2,4,6-pregnatriene-20-one-3,17 α -diol-diacetate

16-methylene-6-chloro-2,4,6-pregnatriene-20-one-

3,17 α -diol-diacetate

16-methylene-6-methyl-2,4,6-pregnatriene-20-one-

3,17 α -diol-diacetate

16-methylene-6-fluoro-2,4,6-pregnatriene-20-one-

3,17 α -diol-diacetate

16-methylene-6-chloro-2,4,6-pregnatriene-20-one-

3,17 α -diol-diacetate

70 6-methyl-2,4,6-pregnatriene-20-one-3,17 α -diol-diacetate

6-chloro-2,4,6-pregnatriene-20-one-3,17 α -diol-diacetate

6-fluoro-2,4,6-pregnatriene-20-one-3,17 α -diol-diacetate

The new steroid-3-enol-acylates are particularly suitable for oral administration. They can be worked into pills, tablets, dragees, solutions or emulsions for oral application by the customary methods of preparation.

The therapeutic effect of the new compounds is substantially higher than that of the basic 3-keto-4,6-diene-steroids. Thus for instance in the Clauberg test on rabbits, 16 - methylene-2,4,6-pregnatriene-20-one-3,17 α -diol-diacetate upon oral application exhibits 3400 times the action of progesterone, while 16-methylene-4,6-pregnadiene-3,20-dione-17 α -ol-acetate has only 460 times the action of progesterone. Similarly, in this test 6-chloro-4,6-pregnadiene-3,20-dione-17 α -ol-acetate is 4500 times more effective than progesterone while 6-chloro-2,4,6-pregnatriene-20-one-3,17 α -diol-diacetate is 5700 times more effective. The best preparations available on the market, namely nor-ethynodiol-2 and 6 α -methyl-17 α -acetoxy-progesterone have on the other hand only 600 and 1500 times the effect of progesterone respectively.

In clinical experiments, the new compounds are administered as tablets of 1 and 2 mg., a dose of one tablet twice a day being on the average sufficient.

The invention thus constitutes a substantial advance in the art of providing orally effective progestagens.

The following are examples in accordance with this invention:

Example 1

1 gram of 4,6-pregnadiene-3,20-dione-17 α -ol-acetate is dissolved together with 0.1 gram of p-toluene sulfonic acid in 40 ml. of benzene. 20 ml. of the solution are distilled off and 10 ml. of isopropenyl acetate added. Thereupon the reaction mixture is heated under reflux in a nitrogen atmosphere for 4 hours. The solution is then cooled, the p-toluene sulfonic acid neutralized with a small amount of anhydrous sodium acetate, and the reaction mixture concentrated under reduced pressure. The residue is extracted in ether, and the ethereal solution shaken with dilute sodium bicarbonate solution, dried with sodium sulfate and concentrated. From methanol there crystallizes 2,4,6-pregnatriene-20-one-3,17 α -diol-diacetate. M.P. 228-229° C.; (α)_D-75° (dioxane); λ_{max} 300 m μ .

E_{1\text{cm.}} 342

Example 2

1 gram of 6-fluoro-4,6-pregnadiene-3,20-dione-17 α -ol-acetate is heated in 16 ml. of acetic anhydride together with 6.4 ml. of acetyl chloride and 0.64 ml. of pyridine for 3 hours at 100° C. Thereupon the reaction mixture is concentrated in vacuum and the residue recrystallized from methanol. 6-fluoro-2,4,6-pregnatriene-20-one-3,17 α -diol-acetate is obtained.

Example 3

In a manner similar to Example 1, 16-methylene-2,4,6-pregnatriene-20-one-3,17 α -diol-diacetate is prepared from 16 - methylene-4,6-pregnadiene-3,20-dione-17 α -ol-acetate. M.P. 170-172° C.; (α)_D-187.5°; λ_{max} 300 m μ .

E_{1\text{cm.}} 335

Example 4

In a manner similar to Example 1, 6-methyl-2,4,6-pregnatriene-20-one-3,17 α -diol-diacetate is prepared from 6-methyl-4,6-pregnadiene-3,20-dione-17 α -ol-acetate.

Example 5

In a manner similar to Example 1, 16-methylene-6-methyl - 2,4,6 - pregnatriene - 20 - one - 3,17 α - diol-diacetate is prepared from 16-methylene-6-methyl-4,6-pregnadiene-3,20-dione-17 α -ol-acetate.

Example 6

In a manner similar to Example 2, 6-chloro-2,4,6-

75

pregnatriene-20-one-3,17 α -diol-diacetate is prepared from 6 - chloro - 4,6 - pregnadiene - 3,20 - dione - 17 α - ol-acetate. Melting point 141-142° C., λ_{max} 301 m μ .

5

E_{1\text{cm.}} 308

(α)_D-47° (dioxane).

Example 7

In a manner similar to Example 2, 16 - methylene - 6 - fluoro - 2,4,6 - pregnatriene - 20 - one - 3,17 α - diol - diacetate is prepared from 16 - methylene - 6 - fluoro - 4,6 - pregnadiene - 3,20 - dione - 17 α - ol - acetate.

15

Example 8

In a manner similar to Example 2, 16 - methylene - 6 - chloro - 2,4,6 - pregnatriene - 20 - one - 3,17 α - diol - diacetate is prepared from 16 - methylene - 6 - chloro - 4,6 - pregnadiene - 3,20 - dione - 17 α - ol - acetate.

20

Example 9

1 gram of 6 - chloro - 4,6 - pregnadiene - 3,20 - dione-17 α - ol - acetate is heated for 3½ hours at 100° C. with 15 ml of butyric anhydride, 7 ml of butyrochloride and 0.7 ml of pyridine. The reaction mixture is concentrated in vacuum, and 6 - chloro - 2,4,6 - pregnatriene - 20 - one-3 - butyrate - 17 α - acetate recrystallized from methanol. Melting point: 157 to 159° C.

The starting materials employed in preparing the compounds hereinafter claimed are described in the following patents and scientific literature, to wit:

4.6 - pregnadiene - 3,20 - dione - 17 α - ol or the corresponding 17-acetate, for claim 2, U.S. Patent 2,739,974; 16 - methylene - 3,20 - dione - 17 α - ol or the corresponding 17-acetate, for claim 3, Tetrahedron Letters, No. 16, page 22, 1960; 16 - methylene - 6 - methyl - 4,6 - pregnadiene - 20 - one-17 α - ol or the corresponding 17-acetate, for claim 4, Belgian Patent 594,445; 6 - dehydro - 6 - methyl - 17 α - acetoxyprogesterone, for claim 7, JACS, vol. 81, page 3485, 1959; 6 - dehydro - 6 - chloro - 17 α - acetoxyprogesterone, for claims 8 and 10, JACS, vol. 81, page 3485, 1959; 6 - dehydro - 6 - fluoro - 17 α - acetoxyprogesterone, for claims 9 and 11, JACS, vol. 81, page 3485, 1959.

It will be understood that the foregoing description of the invention and the examples set forth are merely illustrative of the principles thereof. Accordingly, the appended claims are to be construed as defining the invention within the spirit and scope thereof.

We claim:

1. 2,4,6 - pregnatriene - 20 - one - 3,17 α - diol - diacetate.
2. 16 - methylene - 2,4,6 - pregnatriene - 20 - one - 3,17 α - diol - diacetate.
3. 16 - methylene - 6 - methyl - 2,4,6 - pregnatriene - 20 - one - 3,17 α - diol - diacetate.
4. 6 - methyl - 2,4,6 - pregnatriene - 20 - one - 3,17 α - diol - diacetate.
5. 6 - chloro - 2,4,6 - pregnatriene - 20 - one - 3,17 α - diol - diacetate.
6. 6 - fluoro - 2,4,6 - pregnatriene - 20 - one - 3,17 α - diol - diacetate.
7. 6 - chloro - 2,4,6 - pregnatriene - 20 - one - 3 - butyrate - 17 α - acetate.
8. 6 - fluoro - 2,4,6 - pregnatriene - 20 - one - 3 - butyrate - 17 α - acetate.
